UNITED STATES PATENT OFFICE.

THOMAS SCHUSTER, OF PHOENIX, ARIZONA.

MULTIPLE-PIPE MOLD.

Application filed February 18, 1924. Serial No. 693,592.

To all whom it may concern:

Be it known that I, THOMAS SCHUSTER, a citizen of the United States, residing at Phoenix, in the county of Maricopa and State of Arizona, have invented certain new and useful Improvements in Multiple-Pipe Molds; and I do declare the following to be a full, clear, and exact description of the invention, such as will enable others skilled in the art to which it appertains to make and use the same.

My invention relates to improvements in cement molds and the present disclosure is directed primarily to a mold adapted for the simultaneous casting of a plurality of cement pipes or tiles.

One object of the invention is to provide a multiple mold which may be easily and rapidly operated to simultaneously produce a plurality of pipe sections or the like, of uniform size and quality.

In the preferred form of construction, each mold is provided with an expandible and contractible core and a further object is to provide a novel construction and association of parts for moving a core expander into and out of the lower end of the core, contraction of said core for removal being permitted when said expander is disengaged therefrom, while insertion of said expander places the core in condition for use.

In the construction disclosed, a plurality of the core expanders are carried by a horizontal vertically movable bar and another object of the invention is to provide unique means for raising and lowering this bar or a similar bar which might possibly be used for other purposes on analogous molds.

Yet another object is to provide unique means for holding the molds in spaced relation for use, said means however being removable to permit the molds to be removed from the completed pipes or the like.

A still further aim is to provide unique sectional bell forms for the pipe sections, the sections of said forms being connected with each other in a novel manner.

Yet another object is to provide an improved form of contractible core provided at its upper end with novel means for limiting its expansion when an expander is inserted into such end.

Further objects are to provide novel means for filling the molds and to produce unique centering means for their cores.

With the foregoing and minor objects in

view, the invention resides in the novel subject matter hereinafter described and claimed, the description being supplemented by the accompanying drawings.

Figure 1 is a longitudinal sectional view partly in elevation, showing a multiple mold constructed in accordance with my invention.

Figure 1^a is a plan view of the mold filling trough and core centering means carried thereby.

Figure 2 is a fragmentary view similar to Fig. 1, but illustrating the core expanders moved to a lowered inoperative position.

Figure 3 is a horizontal sectional view on line 3—3 of Fig. 2.

Figure 3^a is an enlarged sectional view of the mold fastener shown more particularly in Fig. 3.

Figure 4 is a vertical transverse sectional view as indicated by lines 4—4 of Fig. 1.

Figure 5 is a perspective view of portions of the mold shown in the preceding figures.

Figure 6 is a perspective view of a number of the core expanders and their carrying and operating means.

Figure 7 is a perspective view of the core shown in certain of the preceding figures, said core being in its contracted position.

Figure 8 is a fragmentary view similar to Fig. 7, but illustrating the manner in which the core is expanded at its upper end.

Figure 9 is a perspective view showing a mold which may be used in place of those illustrated in the preceding figures.

Figure 9^a is a fragmentary perspective view of the opposite side of the mold shown in Fig. 9.

Figure 10 is a perspective view illustrating a different form of core.

Figure 11 is a fragmentary plan view showing a form of mold positioning means which differs from the corresponding means shown in views above described.

Figure 12 is a perspective view showing a still further form of mold positioning means.

Figure 13 is a perspective view illustrating yet another variation of the mold positioning means.

Figure 14 is a fragmentary view similar to Fig. 1 illustrating molds of a different construction.

Figure 15 is a transverse sectional view on line 15—15 of Fig. 14.

Figure 16 is a horizontal sectional view on line 16—16 of Fig. 14.

Figure 17 is a disassembled perspective view of portions of the molds shown in Figs. 14, 15 and 16.

In the drawings above briefly described, 5 the numerals 1 designate a plurality of parallel transverse sills from whose ends, posts 2 rise rigidly, the upper ends of said posts being connected by horizontal bars 3 while similar bars 4 connect said posts at lower 10 points. A plurality of parallel longitudinal stringers 5 are secured upon the sills 1 in spaced relation, to support a plurality of rows of pipe molds 6. Each row of these molds may well be formed of two units as 15 shown in Fig. 5, said units being of stamped metal in most instances with slots 7, through which appropriate releasable fasteners 8 are passed to secure them together. Each fastener 8 is preferably of the construction de- 20 tailed in Fig. 3^a, in which a bolt is shown formed of two telescopic sections 8^a and 8^b one of which is squared or otherwise shaped to pass through a correspondingly shaped opening in the other section. The two bolt 25 sections are secured together by threading a nut 8^c on the inner section, and the outer ends of each section is formed with a flat head 8^d. The bolts pass rotatably through openings 7 in one unit or section of the molds 30 and are insertible through slots 7^a in the other section or unit, and by turning the bolts by grasping either head 8^d, they may be disposed for connecting or disconnecting the two mold sections or units. The edges of 35 the slots 7^a are preferably reinforced as at 7^b.

The lower ends of the molds 6 are shown provided with bell forms 9 to co-operate with suitably shaped bottom plates 10 in 40 forming bells at the lower ends of the pipes being cast. The bottom plates 10 are formed with central openings 11 into which the lower ends of tubular, expandable cores 12, are insertible. For the purpose of expanding 45 these tubular cores 12, suitable core expanders 13 are used, for reception in their lower ends. While the cores may be of any desired form, I have shown them in most views as formed of sheet metal, bent into the 50 form of a tube with slidably overlapping edges 14 (see Figs. 7 and 8). When these cores are in place and the expanders 13 are disposed in their lower ends, such ends are expanded to their proper diameter and so 55 held. Additional expanders 15 are insertible into the upper ends of the cores 12 to expand them to the proper extent and each of these expanders, may well be of sleeve-like form, with a handle 15^a. In order to limit 60 the expansion of the upper ends of the core, I prefer to provide said upper ends with rings 16 which surround them, each ring being secured at at least one point to its respective core. If desired, a chain or the 65 like 17 may connect diametrically oppo-

site portions of the core 13 and extend across the interior of such core as shown in Fig. 8, so that when the expander 15 is removed, said chain or the like may be pulled inwardly thus contracting the core and 70 withdrawing it from the completed pipe.

For simultaneously filling the molds 6 of any row, I have provided a trough 6^a to rest on rails 6^b supported by the posts 2, said trough having mold receiving openings 6^c 75 in its bottom, whose walls are inwardly declined as shown. Cement or the like poured in the trough 6^a will run readily into the numerous molds 6 around the cores 12 which are centered by novel means carried by the trough. In the present showing, this means comprises transverse arms 6^d hinged at 6^e to one side of the trough and having pins 6^f receivable in openings 6^g in the handles 15^a. 80

In Fig. 10, a form of core has been illustrated, comprising two sections 18 and 19 each of slightly more than semi-circular form, with their edge portions in overlapping relation. This form of core may be 90 used with the expanders above described, and I have illustrated a ring 20 thereon to limit its expansion.

For the purpose of holding the numerous 95 molds 6 in proper position, I have shown upper and lower mold-positioning means. In the form of construction shown in most views, these positioning means comprise horizontal bars 21 disposed at opposite sides of the several rows of molds and having inner edges of segmental formation (22) 100 to engage the molds. The bars 21 rest upon the bars 3 and 4 above described and in order to hold them in proper engagement with the molds, longitudinal wedge bars 23 are preferably provided between the bars of adjacent rows of molds.

In Fig. 12, a different form of mold-positioning means has been shown, as comprising a pair of parallel angle bars 24 and cross plates 25 extending between them with their adjacent edges of segmental form, as indicated at 26. This construction is intended primarily for use when, instead of using the molds 6 above described, separate one-piece molds such as the one indicated at 27 in Fig. 9, are employed. In this last named figure, the mold 27 is provided with a suitable arrangement of interfitting flanges or the like 28 on its edges and a suitable clasp or fastener 29 is provided to hold the mold in contracted position and to permit expansion thereof when it is to be removed from the finished product. To allow expanding and contracting movement of the bell 27^a of mold 27, it is split at 27^b Fig. 9^a and the split is covered by a thin plate 27^c loosely connected with the bell for instance by rivets or the like 27^d 115 passing through slots 27^e. 120

In Fig. 13, mold-positioning means has been illustrated, comprising a pair of parallel bars 30 carrying bent rods 31 which are shaped to jointly embrace suitable 5 molds of any character, such as the molds 27 or 6.

The core expanders 13, above described, are carried by longitudinal, horizontal bars 32 disposed between the sills 5 and normally 10 flush with the upper sides of the latter, to assist in supporting the molds. In the construction shown, the bars 32 are of channel form with their side flanges 33 turned downwardly. For supporting these bars, parallel 15 links 34 and hand levers 35 have been shown, said links and levers being pivoted to the flanges 33 and having their lower ends pivoted to longitudinally slidable bars 36 which are positioned under the bars 32. In 20 the present showing, the bars 36 are of channel form and may rest slidably upon the sills 1, the links and levers being pivoted to the upstanding side flanges of said bars. These flanges are formed with longitudinal 25 slots 37, and transverse straps 38 secured to the sills 1, pass across the bars and through said slots to properly guide the latter and retain them in place. The bars 32 are guided in their vertical movement, by vertical bolts or the like 39 whose lower ends may slidably rest upon the bars 36. Between their ends, the levers 35 are fulcrumed at 40 to the ends of the bars 32 and it will be seen that by grasping these levers and operating them, the bars 36 may be slid longitudinally, thus causing the links 34 to raise or lower the bars 32 as occasion may require. Thus, the core expanders 12 may be raised to operative positions, or lowered to permit 30 contraction and removal of the cores. Also, attention may be directed to the fact that in some instances, the vertically movable bars 32 might perform functions other than carriers for the expanders 13. For instance, in 35 casting any objects which do not require the use of cores, these cores may be removed from the bars 32 and the latter would then co-operate with the stringers 5 in supporting the molds and might possibly carry shaping devices or the like, for the objects being cast.

In Figs. 14 to 17, I have shown a different mold construction, in which the body portions of the molds 42 are truly cylindrical and are longitudinally split, said body portions being provided with appropriate clasps or fasteners 43 for normally holding them in proper position, but for permitting expansion thereof for removal. The lower ends of these molds co-operate with sectional 55 bell forms 44 which are preferably of cast metal, each form 44 being divided on a line extending longitudinally of its row of molds, into two halves 45. The halves at each side of any row of molds, are carried by an angle iron bar 46 and a flat bar 47 which are se-

cured to suitable bosses 48 with which said halves are provided. The inner ends of these halves are formed with flanges 49 parallel with the dividing line of the forms 44 and in abutting relation with each other 70 when the halves are assembled for use. To hold these halves in assembled relation, I have shown hooks 50 on the bar 46 of one row of the halves 45 to engage the flanges 49 on the other row of such halves. At their 75 upper portions, the forms 44 are preferably flared to tightly receive the lower ends of the molds 42.

From the foregoing, taken in connection with the accompanying drawings, the construction and operation of the mold will be readily understood and it will be seen that it will be very advantageous for performing numerous kinds of work, but primarily for the formation of pipe or tile sections, 80 either with or without bells.

As excellent results may be obtained from the details disclosed, they may be followed if desired; but within the scope of the invention as claimed, numerous changes may be 90 made.

I claim:

1. In a mold having a vertically movable member at its lower end; a second member below the first named member, means slidably mounting said second member for horizontal movement, and means interposed between the two members and controlled by the sliding movement of said second member for effecting vertical movement of the first named member. 95
2. In a mold having a vertically movable member at its lower end adapted to be lowered to remove the product; a horizontally movable slide under said vertically movable member, and parallel linkage connecting said member and slide, whereby sliding movement of the latter will vertically move the former. 105
3. In a multiple mold having a horizontally elongated vertically movable bar at the lower ends of its molds, a second horizontally elongated bar under said first named bar, means mounting said second bar for longitudinal sliding, and parallel linkage connecting the two bars, whereby longitudinal sliding of said second named bar will effect vertical movement of the first named bar. 115
4. A structure as specified in claim 2; together with a hand lever fulcrumed to said vertically movable member and pivoted to said slide for effecting sliding of the latter and also exerting pressure directly on said movable member in a vertical direction. 120
5. In a multiple mold having a vertically movable bar at the lower ends of its molds, and a base under said bar; a channel bar resting slidably on said base and having longitudinal slots in its side flanges, straps 130

- passing across said bar and through said slots, parallel links pivoted to said vertically movable bar and to the side flanges of said channel bar, and a hand lever fulcrumed to one end of said vertically movable bar and pivoted to said channel bar.
6. A device of the class described comprising a pair of horizontally spaced horizontal mold supports, a horizontal member normally disposed between and flush with the upper sides of said supports, a mold supported jointly by said supports and member and having an expansible core, a core expander rising from said member into said core, and means for lowering said member and expander to permit contraction of said core.
7. A device of the class described comprising mold supporting means, a mold supported thereby and having an expansible core, a vertically movable member under said core having on its upper side a core expander received in said core, and means for raising and lowering said member.
8. A device of the class described comprising a frame structure having mold-supporting means and including additional spaced horizontal supports above said supporting means, vertical molds resting on said supporting means, and horizontally disposed segmental mold-positioning means engaged with said molds and resting on said spaced horizontal supports.
9. A device of the class described comprising a frame structure having mold supporting means and including additional spaced horizontal supports above said supporting means, vertical molds resting on said supporting means and disposed in parallel rows, horizontally disposed segment bars resting on said spaced supports, and engaging opposite sides of said rows of molds, and wedging means between the segment bars of adjacent rows.
10. A device of the class described comprising a pair of spaced parallel sills spaced parallel pairs of stringers extending between and secured to said sills, posts rising from the ends of said sills, horizontal bars over said sills secured to said posts, parallel rows of vertical molds supported by said pairs of stringers and having expansible cores, vertically movable horizontal bars between said stringers having core expanders receivable in said cores, and segmental mold positioning means engaging opposite sides of said rows of molds and resting on said first named horizontal bars.
11. A device of the class described comprising mold supporting means, a vertical mold resting thereon and rising therefrom, said mold having an expansible core, a vertically movable core expander insertible upwardly into the lower end of said core, and means under the mold for vertically moving said expander.
12. A device of the class described comprising mold supporting means, a vertical mold supported thereby and including an expansible tubular core and a bottom plate, having an opening through which the core is insertible, and a core expander insertible upwardly into said core.
13. A device of the class described comprising a mold having an expansible core and an expander in the upper end of said core, a filling trough communicating with said mold, and core-centering means carried by said trough and engageable with said expander.
14. A device of the class described comprising a mold having a core provided at its upper end with an opening, a filling trough communicating with said mold, and a pivoted arm carried by said trough and having a downwardly extending pin receivable in the aforesaid opening to center the core within the mold.
15. A structure as specified in claim 13; said expander having an opening in its upper end, said centering means comprising a pivoted arm having a downwardly extending pin receivable in said opening.
16. A multiple pipe mold comprising a row of spaced bell forms, each divided longitudinally of the row into two separable halves having abutting flanges parallel with the line of division of said forms, a pair of longitudinal bars secured to said halves respectively for holding them in fixedly spaced relation, and hooks pivoted to the bar of one row of halves and engageable with the flanges of the other row of halves to hold the forms together.
17. An elongated mold having a bell at one end and having a split throughout its length, said bell having another split, and a loosely held plate extending across the last named split.
18. A device of the class described comprising a tubular expansible and contractible mold member, means for expanding the same, and a ring surrounding said mold member to limit its expansion, said ring being attached to said mold member at least one point.
19. In combination with a two-part mold having a slot in one part and a smaller opening in the other part; a bolt swiveled in said opening and receivable in said slot, said bolt consisting of two telescopic sections relatively non-rotatable and having operating heads at their outer ends, one of which may either pass through or extend across said slot.
- In testimony whereof I have hereunto affixed my signature.

THOMAS SCHUSTER,
